(57) **CLAIM**

The ornamental design for a decorative fireplace, as shown and described.

DESCRIPTION

FIG. 1 is a perspective view depicting a new design for a decorative fireplace, with no claim being made to the bottom or rear of the fireplace;

FIG. 2 is a front elevation view of the decorative fireplace; FIG. 3 is a side elevation view of the decorative fireplace; and,

FIG. 4 is a top plan view of the decorative fireplace. The broken lines shown in the drawings are for illustrative purposes only and form no part of the claimed design.
